HYPOCHLORITE SWEETENING PROCESS

Richard C. Brandon, Elizabeth, and Minor C. K. Jones, Mountainside, N. J., assignors to Standard Oil Development Company, a corporation of Delaware

Application April 8, 1949, Serial No. 86,152

3 Claims. (Cl. 196—29)

1

The present invention is concerned with an improved sweetening process. The invention is more particularly concerned with the removal of mercaptan compounds, particularly those mercaptan compounds which have heretofore been relatively difficult to remove from hydrocarbon fractions, especially from those fractions boiling in the motor fuel, kerosene, Diesel oil and heating oil boiling ranges. In accordance with the present invention a feed hydrocarbon oil characterized by containing mercaptan compounds is contacted with a hypochlorite treating solution which is characterized by containing a high concentration of free hydroxide.

In accordance with a preferred adaptation of the present invention an uncracked feed hydrocarbon stream is treated with a hypochlorite solution of this character under conditions whereby unexpected and desirable results are secured. A particular embodiment of the present invention comprises treating a prime cut hydrocarbon fraction, especially a fraction boiling in the kerosene boiling range, (350° to 550° F.) with a hypochlorite solution which is characterized by containing a high concentration of free hydroxide and a high concentration of a chloride salt.

It is well known in the art to treat petroleum oils by various procedures in order to remove objectionable compounds, as for example, sulfur compounds therefrom. For example, it is known to treat petroleum fractions boiling in the motor fuel boiling range and in the general range below about 700° F. with various chemical reagents such as sodium or potassium hydroxide solutions. It is also known to treat sulfur-containing feed oils with a so-called, "Doctor treat" wherein the oil is contacted with a lead oxide solution in the presence of free sulfur. This treatment converts the objectionable mercaptan compounds to relatively innocuous alkyl disulphides.

It has also been suggested that objectionable mercaptan compounds be removed from hydrocarbon fractions particularly those boiling below about 700° F. by treating the same with a hypochlorite solution, as for example, with sodium or calcium hypochlorite. The mercaptans present react with hypochlorite solution to form alkyl disulphides, a metal chloride and water. The alkyl disulphides remain in the oil and are relatively harmless, while the chloride is removed with the aqueous phase. However, this process has not been particularly attractive since it has been necessary to use relatively large amounts of the treating solution in order to obtain satisfactory removal of the mercaptans. It has also been suggested that a relatively small amount of free hydroxide be used in conjunction with the hypochlorite solution. Relatively high concentrations of hydroxide have been avoided since it was felt that the presence of the hydroxide tended to impair the conversion of the mercap-

2

tans to disulphides. Furthermore, as pointed out heretofore, sodium hydroxide per se will not function to remove satisfactorily the mercaptans, particularly the higher boiling mercaptans, from the oil containing the same.

It has now been discovered, however, that if the hypochlorite solution contains a relatively high concentration of free hydroxide, as for example, sodium hydroxide, unexpected and desirable results will be secured. It has also further been discovered that if the hypochlorite solution containing a relatively high concentration of hydroxide also contains a relatively high concentration of a chloride salt, as for example sodium chloride, still further desirable results are secured.

The present invention may be readily understood by reference to the drawing illustrating one embodiment of the same. Referring specifically to the drawing, a feed oil, which for the purpose of illustration is assumed to be a kerosene boiling in the range from about 340° F. to 530° F. and which contains mercaptans is introduced into the system by means of feed line 1. In accordance with one adaptation of the invention, a hypochlorite solution which for the purpose of illustration is assumed to be a sodium hypochlorite solution, and which contains a high concentration of an alkali hydroxide, as for example sodium hydroxide, is introduced into line 1 by means of line 2. These streams are mixed in mixing zone 3 and then introduced into a settling zone 4. It is to be understood that settling zone 4 may comprise any suitable number and arrangement of settling stages. A treated oil free of mercaptans is withdrawn from zone 4 by means of line 5. This oil may be further refined or handled in any manner desirable. Generally, this oil is washed with a relatively strong caustic solution, as for example, a sodium hydroxide solution, or it may be clay filtered or rerun in a distillation operation. The hypochlorite solution is withdrawn from zone 4 by means of line 6 and is preferably recycled to line 1. In a continuous operation a portion of the spent treating solution may be withdrawn from the system by means of line 7 and handled as desired.

The treating solution is maintained at the desired concentration and composition by any suitable means. A preferred method is to introduce sodium hydroxide into zone 3 by means of line 8. The sodium hydroxide solution is converted to a sodium hypochlorite solution by introducing chlorine into zone 8 by means of line 10. The extent that chlorine is introduced into zone 8 is adjusted so that the resulting hypochlorite solution contains a relatively high concentration of free sodium hydroxide. This solution is then introduced into line 2 by means of line 11 and mixed with the oil as previously de-

scribed. In accordance with a preferred adaptation of the invention additional chloride as for example, sodium chloride, is introduced into the hypochlorite solution in zone 8 by means of line 12.

The present invention is broadly concerned with the removal of mercaptans from hydrocarbon fractions boiling below about 700° F. It is particularly directed toward the removal of mercaptan compounds from uncracked hydrocarbon fractions, especially those fractions boiling in the range from about 300° F. to 600° F. In accordance with the present invention, a hypochlorite solution containing a relatively high concentration of free hydroxide is employed. The hypochlorite solution is preferably a sodium or lithium hypochlorite solution. However, any alkali metal or alkali earth metal may be used. Suitable metals for example are lithium, potassium, calcium, barium and strontium.

The amount of hypochlorite solution employed may vary appreciably, as for example, from about 5 to 50% by volume of the hypochlorite solution based upon the volume of oil being treated. However, in general it is desired to maintain the quantity of treating solution as low as possible. This is essential since the hypochlorite solution is a relatively strong oxidizing agent and if an excess of oxygen be present, various side reactions occur other than the formation of the disulphides from the mercaptans. One side reaction which occurs is that oil-soluble sulfonic acids are formed. Also, sulfonyl chlorides are formed if too great a quantity of hypochlorite solution be utilized. Another reaction which occurs is the formation of sulfones from thioethers which may be present in the feed oil. These undesirable compounds tend to decompose upon further refining of the oil resulting in the formation of acidic constituents as for example hydrogen chloride and sulfur dioxide.

In accordance with the process of the present invention it is therefore desirable that the oil be treated with not greater than 20% by volume of the hypochlorite solution. In general it is preferred that the quantity of hypochlorite solution employed be less than about 10%, preferably in the range from about 2 to 5% of hypochlorite solution based upon the oil being treated.

The concentration of the hypochlorite solution likewise may vary appreciably and will be a function to some extent of the amount of solution utilized. However, in general it is preferred that the concentration of the hypochlorite solution be

The amount of free sodium hydroxide present may vary appreciably but in accordance with the present invention it is preferred that not less than about 50 grams per liter of treating solution and preferably from 100 to 300 grams per liter of free sodium hydroxide be present. If sodium chloride be used in conjunction with the free sodium hydroxide and the hypochlorite solution, it is preferred that from about 50 to 200 grams per liter of sodium chloride or equivalent be utilized based upon the treating solution.

The time of contact may be varied appreciably depending upon other operating conditions, however, in general it is preferred to have the time of contact not in excess of about 10 minutes. Desirable times of contact are in the range from about 2 to 5 minutes.

The present invention may be more fully understood by the following examples illustrating the same.

EXAMPLE 1

A hydrocarbon fraction boiling in the range from about 100° F. to 320° F. and secured from a catalytic cracking operation had a ASTM gum¹ of 3 and an ASTM breakdown² of 340. This oil was treated with 50% by volume of a hypochlorite solution containing 10.7 grams per liter of sodium hypochlorite and 2 grams per liter of sodium hydroxide. The resulting product had a gum content of 12 and a breakdown of 160.

EXAMPLE 2

An operation was conducted similar to that described with respect to Example 1 except that the feed oil was a cracked oil boiling in the range from about 100° F. to 430° F. The feed oil had an ASTM gum content of 19 and an ASTM breakdown of 360. The treated product had an ASTM gum content of 28 and an ASTM breakdown of 200.

From the above two examples, it is apparent that the hypochlorite solution of the present invention is not particularly adapted to the treatment of cracked oils.

EXAMPLE 3

An uncracked kerosene fraction containing mercaptans and boiling in the range from about 340 to 530° F. was contacted with various hypochlorite solutions for contact times of about 2 minutes.

The results of these operations are listed as follows:

Effect of excess sodium hydroxide in hypochlorite sweetening of Iraq kerosene in two minutes' contact time

Operation	Hypochlorite Analysis		Treat, Vol. Per Cent	Doctor Test	Acidity, M ₁ N/10 KOH/100 ml.	Chlorine, Wt. Per Cent
	NaOCl, g./l.	NaOH, g./l.				
1	10.7	2.1	25	DNP		
2	10.7	2.1	50	pass	2.25	0.002
3	10.7	26	10	DNP		
4	10.7	26	25	pass	1.36	0.004
5	10.8	51	10	do	1.44	0.002
6	10.6	78	10	do	1.25	0.004
7	10.5	107	5	DNP		
8	10.5	107	10	pass	0.92	0.002

not in excess of about 60 grams of sodium hypochlorite or equivalent per liter and preferably be in the range from about 2 to 12 grams per liter of treating solution.

These results show that the kerosene can be sweetened with progressively smaller amounts

¹ Milligrams of gum per 100 milliliters, ASTM Test D-381-36, "Gum Content of Gasoline (Air-jet method)."

² ASTM Designation D-525-46.

of hypochlorite as excess sodium hydroxide is increased from 2 to 51 g./l.

From the above it is apparent that very desirable results are secured by utilizing a hypochlorite solution containing a relatively high concentration of sodium hydroxide.

excess sodium hydroxide is employed, and also when a relatively low volume of treat is utilized.

EXAMPLE 6

5 Additional operations were conducted wherein an excess of sodium chloride was used in conjunction with an excess of sodium hydroxide. The results of these operations are as follows:

Effect of excess sodium chloride in hypochlorite sweetening of Iraq kerosene (14 mg. mercaptan sulfur/100 ml.)

Operation	Hypochlorite Composition ¹			Treat, Vol. Per Cent	Doctor Test	Residual Acidity	Chlorine, Wt. Per Cent
	NaCl, g./l.	NaOH, g./l.	NaOCl, g./l.				
1-----	8	1.6	10.4	{ 50	DNP		
				75	Pass	2.30	0.0096
2-----	80	1.6	10.4	{ 50	DNP		
				75	Pass	2.30	0.0096
3-----	8	107	10.6	{ 5	DNP		
				10	Pass	0.92	0.002
4-----	80	105	10.6	{ 5	do	1.06	0.0015

¹ Amounts of sodium chloride shown were weighed into the solutions; NaOH and NaOCl were determined by analysis.

EXAMPLE 4

An uncracked kerosene secured from a West Texas crude and boiling in the range from about 350 to 530° F. which contained 99 milligrams of 30 mercaptan sulfur per 100 milliliters was treated in various operations with the following results.

Effect of excess sodium hydroxide in hypochlorite Sweetening of West Texas kerosene in two minutes' contact time

Operation	Hypochlorite Analysis		Treat, Vol. Per Cent	Doctor Test	Acidity, Ml. N/10 KOH/100 ml.	Chlorine, Wt. Per Cent
	NaOCl, g./l.	NaOH, g./l.				
1-----	55.7	9.0	100	Pass	20.1	0.0347
2-----	55.7	9.0	50	do	13.5	0.0365
3-----	55.7	9.0	25	do	12.1	.0527
4-----	55.7	9.0	15	do	11.3	.0363
5-----	10.6	78.0	50	do	3.3	.021

From the above data it is apparent that for a fixed NaOH concentration, as the quantity of treat increased the tendency to form undesirable sulfonic acids and sulfonyl chlorides increased prohibitively as evidenced by the increase in acidity. On the other hand, in operation 5, wherein an excess of sodium hydroxide was employed, the acidity was appreciably lower.

EXAMPLE 5

Other operations were conducted using an uncracked kerosene, secured from an Iraq crude, and boiling in the range from 350 to 500° F. with the following results:

50 a hypochlorite solution which has a high concentration of sodium hydroxide, unexpected and desirable results are secured.

A very specific embodiment of the present invention is to remove mercaptans from oils containing the same utilizing a hypochlorite solution as described and to contact the treated oil in a 55 subsequent stage with tetraethanol ammonium hydroxide. A preferred concentration is to use from 15 to 25% aqueous solution of tetraethanol ammonium hydroxide. In an operation wherein a 20% solution of tetraethanol ammonium hydroxide was employed it was found that the 60 weight per cent of chlorine remaining in the oil

Iraq kerosene

Operation	Hypochlorite Analysis		Treat, Vol. Per Cent	Doctor Test	Acidity, Vol. N/10 KOH	Chlorine, Wt. Per Cent
	NaOCl, g./l.	NaOH, g./l.				
1-----	10.8	156	2	DNP		
2-----	10.8	156	5	Pass	2.03	0.0044
3-----	10.5	166	2	do	0.48	0.0014
4-----	10.3	220	2	do	0.58	0.0014

It is apparent from the above that excellent results are secured when the amount of hypochlorite is maintained relatively low, when

was reduced to about one-fifteenth of the chlorine content of the oil which was not so treated.

Having described the invention it is claimed:
